Patented May 22, 1917.

2 SHEETS—SHEET 2.

UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

TUCK-FORMING MECHANISM FOR SEWING-MACHINES.

1,227,116.

Specification of Letters Patent.

Patented May 22, 1917.

Application filed June 11, 1915. Serial No. 33,458.

To all whom it may concern:

Be it known that I, JOHN E. CHALMAN, a citizen of the United States, residing at Chicago, in the county of Cook, State of Illinois, have invented certain new and useful Improvements in Tuck-Forming Mechanism for Sewing-Machines, of which the following is a description, reference being had to the accompanying drawing and to the figures of reference marked thereon.

The invention relates to new and useful improvements in a tuck forming mechanism for sewing machines, and more particularly to a tuck forming mechanism of the character shown in the Woodward and McNeil Patent 821,774, granted May 29th, 1906.

An object of the invention is to provide means for holding the fabric properly positioned around the tuck forming ribs while the presser foot is lifted through the action of the feed dog thereon for the feeding stroke.

A further object of the invention is to provide a device of the above character wherein the tucks are formed in the fabric by spaced ribs coöperating with grooves in the presser foot with yielding means for holding the fabric continuously on the work support in advance of the presser foot and between the ribs which project in front of the presser foot to assist in the initial forming of the tucks.

These and other objects will in part be obvious and will in part be hereinafter more fully disclosed.

In the drawings which show by way of illustration one embodiment of the invention,

Figure 1 is a perspective view of a portion of a sewing machine having my improvements applied thereto;

Fig. 2 is a transverse vertical sectional view through the same, showing the feed dog positioned for its return stroke;

Fig. 3 is a detail in vertical section through the work support, showing the presser foot, the needles and the feed dog in raised position for feeding the material;

Fig. 4 is a longitudinal vertical section through the presser foot and the work support, showing the needles in front elevation;

Fig. 5 is a detail in vertical section show-

ing the fabric held on the work support by the auxiliary pressing member;

Fig. 6 is a detail showing diagrammatically the manner of forming the tucks in the material;

Fig. 7 is a bottom plan view of the presser foot; and

Fig. 8 is a top plan view of the throat plate, also showing the feed dog.

The machine to which my improvements are applied is shown in a general way in the Woodward and McNeil patent, above referred to, and consists of a work support 1, 65 an overhanging arm 2, in which reciprocates a needle bar 3, carrying two pairs of needles 4—4 and 5—5. A looper 6 coöperates with the needles 4—4, which are slightly in advance of the needles 5—5 and a looper 7 co- 70 operates with the needles 5—5.

The material is held on the work support by a presser foot 8, carried by a presser bar 9. A feed dog 10 coöperates with the presser foot for feeding the material. Said feed 75 dog 10 is carried by a feed bar 11, which is raised and lowered by an eccentric 12, and said feed bar is reciprocated by a feed rocker 13 in a manner well known in this art.

As clearly shown in Fig. 4, the presser 80 foot is formed with two longitudinal grooves 14 and 15. These grooves extend from end to end of the presser foot and centrally through the needle openings 16 and 17 through which the pairs of needles respectively operate. The throat plate of the machine is provided with ribs 18 and 19, which are adapted to extend respectively into the grooves 14 and 15. These ribs, as clearly shown in Fig. 8, extend into the needle openings 20 and 21 in the throat plates for the respective pairs of needles. The fabric, indicated at F in the drawings, is laid on the work support over the ribs 18 and 19, and when the presser foot is lowered so that the 90 ribs extend into the grooves 14 and 15, respectively, the fabric will be bent, so as to form tucks f and f', or what is sometimes referred to in this art as "air cords". The needles 4—4 pass on the opposite sides of the 95 rib 18, forming the needle loops 4'—4', which are joined by a looper thread 6'. This looper thread joining the needle loops holds the fabric in the form of a tuck. The

100

needles 5—5 pass on opposite sides of the rib 19, forming the needle loops 5'—5', which are likewise joined by a looper thread loop 7', and this locks and forms the tuck f. 5 The feed dog 10 is formed with feed webs 22 and 23, which extend along the outer sides of the ribs from a point in front of the needles to a point in rear of the needles for feeding the material. Said feed dog also 10 has a feeding web 24 directly in rear of the needles. There is still another feeding web 25 which engages the material between the ribs 18 and 19. These feeding webs coöperate to feed the material underneath the 15 presser foot. It is well known that the feed dog 10 when raised into contact with the material for feeding the same also raises slightly the presser foot and then the feed dog sliding along the underface of the 20 presser foot carries the material and positions the same for the next stitching operation, after which the feed dog drops and is returned for the next feeding movement. The presser foot 8, therefore, during the 25 normal feeding of the machine is intermittently raised and lowered slightly from the ribs 18 and 19 and also from the work support between the ribs.

This action of the presser foot between 30 the ribs has in effect a sucking action which causes the material to rise from the work support and this rising of the material is apt to deform the tucks or air cords made on the machine. In order to obviate this 35 difficulty, I have provided an auxiliary pressing member 26, which, as herein shown, is in the form of a roller carried by a pivoted arm 27, which is forked to receive the roller and the pivot pin 28, on 40 which the roller is journaled. Said arm at its rear end is provided with two upwardly turned lugs 29 and 30, which engage a pivot pin 31 passing through brackets 32—32 formed integral with the presser 45 foot. A spring 33 surrounds this pivot pin 31 and bears on the arm 27 so as to normally depress the roller 26. A screw 34 extends through the arm 27 and serves as a limiting stop to limit the downward movement of the arm 27, relative to the presser 50 foot. This arm 27 and the stop are so positioned that when the presser foot is flat on the material and the material on the work support, that is, when the feed dog 10 is depressed, then the roller 26 engages the material between the ribs 18 and 19 in advance of the presser foot and yieldingly holds the material on the work support. Said arm and stop are also so positioned 55 that when the presser foot is raised through the action of the feed dog thereon, said roller still holds the material on the work support, as clearly shown in Fig. 3. The stop may be so positioned as to take a portion 60 of the tension of the roller off from

the material. When the presser foot is raised for the insertion of the material underneath the same, then the stop engages the presser foot and limits the downward movement of the arm 27, so that the arm 70 and the presser roller carried thereby will be bodily raised from contact with the material on the work support. This facilitates the insertion of the material underneath the presser foot. During the normal 75 feeding operation of the machine, however, this auxiliary pressing member 26 holds the material continuously against the work support, while the presser foot is being raised by the feed dog. 80

When the presser foot is raised from the work support through the action of the feed dogs thereon, the grooves will be raised from the ribs to a certain extent and the fabric through the sucking action of the 85 foot may be raised from the ribs. It is found in practice, that it is very difficult to form the ribs and the groove and position the presser foot so that these ribs will move into the grooves with equal friction against 90 the fabric at each side of each groove and, therefore, the up and down movement of the presser foot tends to grip the fabric at one side of one rib more firmly than around the opposite rib and the result is a shifting 95 or a lateral creeping of the tucks in the fabric which, of course, forms an irregularly placed tuck. By my improvement, however, wherein the feed dog is provided with a fabric engaging web located between 100 the ribs, the fabric will be clamped by this section of the feed dog, firmly against the under face of the presser foot when the presser foot is raised, and this prevents the lateral creeping of the fabric. 105

This feed section may be located centrally between the ribs and the placing of the same at one side of the center is purely for the purpose of convenience.

The ribs 18 and 19 project some distance 110 in advance of the presser foot, as clearly shown in Fig. 1 of the drawings. The roller 26 pressing on the fabric between the ribs holds the same continuously against the work support and this positioning of the 115 fabric between the tucks prior to the forming of the tucks through the coöperation of the grooves in the presser foot with the ribs, insures a uniform placing of the tucks. Furthermore, this roller 26 tends to hold the 120 fabric section between the ribs on the work support and in part overcomes the distortion of the tucks due to the up and down movements of the presser foot on the ribs. The presser foot is provided with longitudinal 125 grooves 35 and 36 which become guiding grooves when more than two tucks are formed. For example, after having formed two tucks, when it is desired to form another pair of tucks, and space the same the same 130

distance from the previously formed tucks as the distance between the tucks, then one of the previously formed tucks is run through either the groove 35 or the groove 36, which becomes a guiding groove for positioning the fabric during the formation of the new pair of tucks.

It is obvious that minor changes in the details of construction may be made without departing from the spirit of the invention, as set forth in the appended claims.

Having thus described my invention, what I claim as new and desire to secure by Letters Patent, is:—

1. The combination of a work support, a feeding mechanism including a feed dog located beneath the work support, a presser foot coöperating with said feed dog, said work support having spaced ribs thereon and the presser foot having grooves coöperating with said ribs to form tucks in the fabric, stitching mechanism for stitching the tucks, and means yieldingly engaging the material in advance of the presser foot for holding the same continuously on the work support in advance of the presser foot.

2. The combination of a work support, a feeding mechanism including a feed dog located beneath the work support, a presser foot coöperating with said feed dog, said work support having spaced ribs thereon extending in front of the presser foot, grooves coöperating with said ribs to form tucks in the material, stitching mechanism for stitching the tucks, means carried by the presser foot and engaging the material in advance thereof for holding the material on said tuck forming ribs, and devices for yieldingly pressing said means on the work support when the presser foot is raised through the action of the feed dog.

3. The combination of a work support, a feeding mechanism including a feed dog located beneath the work support, a presser foot coöperating with said feed dog, said work support having spaced ribs thereon extending in front of the presser foot, said presser foot having grooves coöperating with said ribs to form tucks in the material, stitching mechanism for stitching said tucks, a pivoted arm carried by the presser foot and extending forwardly therefrom, a roller pivotally supported by said arm and coöperating with the work support between said ribs, and means for yieldingly depressing said arm.

4. The combination of a work support, a feeding mechanism including a feed dog located beneath the work support, a presser foot coöperating with said feed dog, said work support having spaced ribs thereon extending in front of the presser foot, said foot having grooves coöperating with said ribs to form tucks in the material, stitching mechanism for stitching said tucks, a piv-

oted arm carried by the presser foot and extending forwardly therefrom, a roller pivotally supported by said arm and coöperating with the work support between said ribs, a spring engaging said arm and forcing the same downwardly to cause said roller to engage the material on the work support, and a stop for limiting the downward movement of said arm.

5. The combination of a work support, a feeding mechanism including a feed dog located beneath the work support, a presser foot coöperating with said feed dog and having grooves formed in its under face, said work support having spaced ribs thereon extending in front of the presser foot, said grooves coöperating with said ribs to form tucks in the material, stitching mechanism for stitching said tucks, a pivoted arm carried by the presser foot and extending forwardly therefrom, a roller pivotally supported by said arm and coöperating with the work support between said ribs, a spring engaging said arm and forcing the same downwardly to cause said roller to engage the material on the work support, and a stop for limiting the downward movement of said arm, said stop being adjustable.

6. The combination of a work support, a presser foot, said work support having spaced ribs thereon, said presser foot having grooves formed in its under face coöperating with the ribs to form tucks in the fabric, stitching mechanism for stitching the tucks and a feeding mechanism including a feed dog having a feeding section engaging the material between the ribs.

7. The combination of a work support, a presser foot, said work support having spaced ribs thereon, said presser foot having grooves formed in its under face coöperating with the ribs to form tucks in the fabric, stitching mechanism for stitching the tucks and a feeding mechanism including a feed dog having a feeding section engaging the material between the ribs, and at points outside of said ribs.

8. The combination of a work support, a presser foot, said work support having spaced ribs thereon, said presser foot having grooves formed in its under face coöperating with the ribs to form tucks in the fabric, stitching mechanism for stitching the tucks and a feeding mechanism including a feed dog having a feeding section engaging the material between the ribs, and at points outside of said ribs, each of said feeding sections having their forward ends substantially in line and at the forward end of the presser foot.

9. The combination of a work support, a presser foot coöperating with said work support, said presser foot having parallel grooves formed in its under face, said work support having ribs adapted to extend into

4
said grooves, said ribs projecting some distance in front of the presser foot, yielding means for engaging the fabric in front of the presser foot between said ribs for continuously holding the fabric on the work support, a feed dog coöperating with the presser foot and having feed sections engaging the fabric at each side of and between the ribs adjacent the forward end of the presser foot.

10. The combination of a work support, a presser foot coöperating with said work support, said presser foot having parallel grooves formed in its under face, said work support having ribs adapted to extend into said grooves, said ribs projecting some distance in front of the presser foot, yielding means for engaging the fabric in front of

the presser foot between said ribs for continuously holding the fabric on the work support, a feed dog coöperating with the presser foot and having feed sections engaging the fabric at each side of and between the ribs adjacent the forward end of the presser foot, and stitch forming mechanism including pairs of needles, one pair for each rib, said needles of each pair being disposed respectively on opposite sides of its coöperating rib and a looper coöperating with each pair of needles.

15 In testimony whereof, I affix my signature in the presence of two witnesses.

JOHN E. CHALMAN.
